UNITED STATES PATENT OFFICE

CHARLES R. CUSTIS, OF HARRISON, NEW JERSEY

COMBINED WASHTUB AND HEATER.

1,105,496.

Specification of Letters Patent. Patented July 28, 1914.

Application filed September 30, 1913. Serial No. 792,538.

To all whom it may concern:

Be it known that I, CHARLES R. CUSTIS, a citizen of the United States, residing at Harrison, in the county of Hudson and State 5 of New Jersey, have invented certain new and useful Improvements in Combined Washtubs and Heaters; and I do hereby declare the following to be a full, clear, and exact description of the invention, such as 10 will enable others skilled in the art to which it appertains to make and use the same.

This invention relates to combined wash-tubs and heaters and is designed as an attachment for various types of wooden washing machines, the purpose being to provide 15 means for heating the water and keeping it hot within the wooden tub or casing during the operation of washing the clothes.

In washing machines of the type referred 20 to, when the hot water is placed therein along with the clothes, it soon becomes cold and under this condition the soiled portions of the clothes are not thoroughly cleansed.

My invention is primarily designed for 25 the purpose of overcoming the defect referred to and to provide means for keeping the water constantly at the required temperature to obtain the very best results.

Referring to the accompanying drawings, 30 the figure of the drawing is an enlarged vertical sectional view of the bottom of the tub, showing my invention connected thereto.

Referring to the drawing, the numeral 1 designates the bottom of a wooden tub of 35 an ordinary washing machine.

In carrying out my invention I form a circular opening in the bottom of the tub and in this opening I insert a pan or heat condenser comprising a copper or other metal 40 device having an annular rim 3 which fits closely within the opening in the bottom of the tub, said condenser having a plane imperforate top 4. Surrounding the body portion 3 of the heat condenser as an asbestos 45 packing ring 5, and a metal ring 6 is placed on the top of the packing ring 5. At the lower end of the cylindrical portion 3 of the condenser is an annular flange 7. Disposed intermediate the flange 7 and the 50 lower wall of the bottom 1 is an asbestos packing ring 8 which surrounds the body portion 3 and is provided with a metal ring

9 which fits around the body portion 3, and a series of bolts 10 extend through the ring 6, an asbestos packing ring 5, on the inside 55 of the tub and through the bottom 1 of the tub, and through the packing 8, the flange 7 and the ring 9. These bolts also extend through an annular flange 11 formed upon the extension member 12 which is of cylindrical form and of the same interior diameter as the body portion 3 of the condenser. A heater comprising a gas burner 13 having an enlarged head provided with perforations 60 is connected to a gas supply pipe 14 which 65 may be supported by means of metal bands 14^a, provided with a cock 15.

It will be understood that instead of the gas burner I may use a kerosene, gasoline 70 or other burner.

The operation of my invention may be briefly described as follows: When the burner is lighted, the heat will extend through the imperforate top 4 and keep the water at an equal temperature during the 75 washing operation. The asbestos packing and manner of securing the same around the opening in the wooden bottom will prevent the heat from igniting the wooden bottom of the washing machine. 80

My invention is simple in construction, can be connected to any type of wooden washing machine, and will insure an equable temperature of the water in the tub during 85 the washing operation.

I claim:—

A combined washtub and heater, comprising a washtub provided with an opening in the bottom thereof, a heat condenser fitted in said opening, said condenser comprising 90 a cylindrical portion having an imperforate top, packing rings surrounding the condenser, an extended member to confine the heat within the condenser, and a burner disposed below the condenser for keeping the 95 water in the tub at the required temperature.

In testimony whereof I affix my signature in presence of two witnesses:

CHARLES R. CUSTIS.

Witnesses:

J. B. McCALLUM,
JOHN O'HARE.
